UNITED STATES PATENT OFFICE.

HOWARD L. KRUM, OF CHICAGO, ILLINOIS, ASSIGNOR, BY MESNE ASSIGNMENTS, TO MOKRUM-KLEINSCHMIDT CORPORATION, OF CHICAGO, ILLINOIS, A CORPORATION OF DELAWARE.

TELEGRAPH APPARATUS.

Application filed November 7, 1923. Serial No. 673,237.

The invention relates to telegraphs adapted for use with systems in which the signals comprise permutations of two different line conditions extending through a 5 definite number of time intervals or units, the selecting units of each signal being preceded by a uniform starting interval or unit, and the signals being separated by intervals in which the line is restored to 10 normal condition. The invention seeks to provide improved transmitting and receiving distributors for systems of this sort, together with an improved key-board for controlling the transmitting distributor, distributors and key-board being preferably 15 combined in a single unit.

The invention consists in the features of improvement hereinafter set forth, illustrated in the preferred form in the accompanying drawings and more particularly pointed out in the appended claims.

In the drawings:

Fig. 1 is a plan view of the improved apparatus;

Fig. 2 is a transverse section on the line 2-2 of Fig. 1;

Fig. 3 is a detail section on the line 3-3 of Fig. 1;

Fig. 4 is a front to rear section on the line 4-4 of Fig. 1;

Fig. 5 is a detail longitudinal section on the line 5-5 of Fig. 1;

Fig. 6 shows outline cross sections of the receiver cam;

Fig. 7 is a front to rear section on the line 7-7 of Fig. 1;

Fig. 8 is a detail longitudinal section of the transmitter cam taken on the line 8-8 of Fig. 1;

Fig. 9 shows outline cross sections of different portions of the transmitter cam; and

Fig. 10 is a diagram of the circuit connections.

In its preferred embodiment the apparatus has a hollow cast metal base or frame 10 provided with a front extension 11 and a rear extension 12. Key levers 13 arranged within the upper portion of the base frame have their rear ends in engagement with a common pivot rod 14 carried by lugs 15.

The forward portion of the key levers extend through the slots of a comb bar 16 and have upturned front ends carrying keys

17. A bail 18 pivoted on the forward extension 11 carries a space bar 19 and has a pin and slot connection with the downwardly extending forward end of one of the key levers. The keys are upheld in normal position by spring 20. A set of five permutation bars 21 extend transversely below the key levers, the ends of the bars being guided in slots in oppositely disposed L-shaped brackets 22 fixed within the base frame and supported on anti-friction rollers 23. The brackets 22 are preferably formed 60 of sheet metal stampings and have lugs which carry the shafts or pins 24 upon which the rollers 23 are mounted. Each permutation bar is free to move longitudinally to either one of two positions and each bar has 65 cam lugs 25 having oppositely inclined faces, one such face being provided on each bar for each of the key levers, so that each bar is adapted to be moved to its right-hand position by some of the keys and to 70 its opposite left-hand position by the others. In this way the keys serve to set these bars in different combinations.

At its right-hand end each permutation bar is provided with a notch in its upper edge which engages the rounded lower end of a corresponding selecting finger. The five selecting fingers 26 extend upwardly through an opening in the base frame and are mounted upon a common pivotal support 27 arranged between uprights 29. The fingers 26 control a set of switch shifters in the form of bell cranks 30 mounted upon a horizontal pivot shaft 31 carried by uprights 29. The fingers 26 control a set of switch shifters in the form of bell cranks 30 mounted upon a horizontal pivot shaft 31 carried by uprights 29. Each selecting finger 26 has a hooked lug 32 at its upper end which, as the associated permutation bar is shifted, is moved into and out of position above the end of the horizontal arm of the associated switch shifter. The fingers 26 and bell cranks 30 are held in proper position by spacing washers on the supports 27 and 31, and preferably also, a guide comb bar 32 is provided for the horizontal arms of the bell cranks or switch shifters 30.

There is provided, however, an additional or sixth switch shifter 30' which is not controlled by one of the selecting fingers.

Each bell crank or switch shifter has a hook 33 at its upper end which engages the insulated upper end of a spring contact

finger 34, and each of the latter cooperates with a contact finger 35, the pairs of contact fingers being mounted upon but insulated on a supporting bar 36 carried by the uprights 29. Each spring contact 34 tends to engage its associated contact 35 and also serves to hold a lug 37 on the horizontal arm of the corresponding switch shifter in engagement with the surface of a cylindrical cam 38, the latter being mounted on a horizontal shaft 39 and extending over the horizontal arms of the switch shifters or controllers 30. The cam 38 is provided with a helical series of slots 1, 2, 3, 4, 5 and 6, which, as the cam is rotated, successively pass over the lugs 37 of the switch controllers. As the corresponding recess passes over one of the lugs the associated switch contacts are closed provided the horizontal arm of the switch controller is not held down by the corresponding selecting finger.

The shaft 39 (see Figs. 1 and 8) is journaled at its rear end in a bracket 40 and at its forward end in a bushing 41 carried by the front upright 29. The cam 38 is loose on the shaft 39 but a flange at one end and a recess at the other are engaged by friction washers 42 and 43 which in turn are engaged by discs 44 and 45. Disc 45 is pinned to the shaft and disc 44 is keyed to it, being pressed longitudinally of the shaft by a spring 46 coiled about the shaft and extending between the disc and a collar 47 adjustably fixed on the shaft. A hub 48 fixed to the rear end of the shaft has a gear 49 adjustably fixed thereto by a screw 50 and this gear is connected by a pair of intermediate idle gears 51 with a gear 52 on a shaft 53. Shaft 53 is provided with a worm wheel 54 which meshes with a worm 55 on the shaft of a small electric motor 56. The latter is mounted on the base 10 and is provided with a suitable governor for maintaining its speed uniform, the governor being provided with suitable means by which the speed of the motor may be adjusted.

The transmitter cam is normally held against movement with the shaft 39 by a stop arm or lever 57 (see Figs. 2 and 7). This stop arm is pivotally mounted between its ends, is vertically disposed and its upper end is arranged to engage a shoulder 58 on the forward end of the transmitter cam, such upper end being pressed toward the forward end of the cam by a spring 59. The lower end of the stop arm extends downwardly between two of the keys and carries an adjustable screw 60 which is arranged to be engaged by a lug 61 on a bail 62. The latter is pivotally mounted at its ends and is shifted by any one of the key levers when the latter is depressed to set the permutation bars 21 and selecting fingers 26 to thereby shift the stop arm 57, so that the cam shaft is then rotated by the shaft 39

through the medium of the friction discs or washers 42 and 43.

The selecting fingers are provided at their upper ends with upwardly projecting lugs 63 having beveled upper edges which cooperate with a beveled edge rib on a locking bail 64. The latter is pivotally mounted on the uprights 29 and a spring 69 tends to depress the lock bar and to hold a roller 70 thereon in engagement with the reduced portion of the transmitter cam. A lug 71 on the cam engages the roller 70 in the zero or normal arrested position of the transmitter cam, and thus holds the lock bar 64 in raised position. Shortly after the cam starts the spring 69 depresses the lock bar and holds the selecting fingers 26 and permutation bars in set position and since each bar has an inclined face cooperating with each of the key levers, none of the keys except the ones depressed can be operated until the lock bar is raised.

The receiver cam 72 on the shaft 53 and the associated switch contacts and controllers are similar in construction to those shown and described in connection with the transmitter cam, but the switch controllers of the receiver are uniformly operated in order as the receiver cam rotates and are not variably controlled by selecting fingers. The receiver cam (see Fig. 5) has a flange at one end on which a stop cam 73 is adjustably secured by a screw 74, the latter extending through a slot in the flange of the cam. The stop cam has a circular periphery recessed at one portion and forming a shoulder 75 which is arranged to be engaged by the hooked upper end of a stop arm 76. The latter is mounted upon the frame of a starting magnet 77 and carries the armature of the magnet, a spring 78 serving to hold the stop arm in operative position when the magnet is de-energized.

Fig. 10 is a diagram of the electrical connections. Preferably, as shown, the transmitter contact arms 35 are connected together and to a battery. The transmitter spring contact arms 34 are connected together and either directly to the line as shown or, if desired, to the coil of a transmitting relay. The contacts controlled by the receiver cam are interposed in a local circuit, the receiver contacts 35 being connected respectively to the five selecting magnets 79 and the so-called "sixth pulse" or operating magnet 80 of the receiving printer. The receiver contacts 34 are connected together and to the normally engaged contact 81 of a line relay 82. The receiver start magnet is connected to the normally disengaged contact 83 of the relay and the relay tongue is connected to battery so that the start magnet 77 is energized whenever the normal condition of the line is changed.

As indicated by dotted lines in Fig. 9, the periphery of the transmitter cam is divided

into seven sections, S, 1, 2, 3, 4, 5, and I. Preferably the sections are uniform except that the section I is somewhat greater than the other sections. This section of the cam 5 is in its operative position in the normal arrested or zero position of the cam and thus cooperates with the switch controller 30' to engage the corresponding pair of contacts and normally hold the line closed. As the 10 cam rotates the switch controller 30' will be invariably shifted as the section S of the cam passes through the operating position and thereafter the other switch controllers will be variably operated in accordance 15 with the setting of the permutation bars to close or hold open the other pairs of contacts during the five selecting intervals of the signals. At the end of the signal and before the cam is arrested, the switch controller 20 30' will invariably restore the line to normal condition as the section I of the cam is moved to operating position.

The lug 71 releases the lock bar 64 before the transmitter cam is arrested, so that if 25 the keys are rapidly operated the transmitter cam can be continuously rotated to impart successive signals to the line, but even under such conditions the signals will be 30 separated by intervals of normal line condition which persist as the section I of the cam member passes through the operative position, so that ample opportunity is afforded the cams of the receiver to reach its normal or zero position at the end of each 35 signal and before the starting condition of the succeeding signal is imparted to the line. If the transmitter contacts are directly connected to the line the latter is normally closed, the starting interval is one of no- 40 current and the selecting signals of permutations of current and no-current intervals. By employing the transmitting relay two different line conditions may be currents of opposite polarity. It should also be noted 45 that the ends of the recesses of the transmitter cam overlap to such an extent that the successive intervals of the signals follow one another without intermediate spaces.

The receiving line relays at the different 50 stations vibrate their tongues in response to the conditions imparted to the line by a transmitter and with the circuit arranged as shown will respond to the conditions imparted to the lines by transmitters located 55 at one or more distant stations, and also imparted to the line by the local transmitter to form a home record. During the initial starting interval of each signal, the normal line condition is changed and the armature 60 of the line relay engages its contact 83 and closes the circuit of the starting magnet 77. Thereupon the receiver cam 72 is rotated and it cooperates with its switch controllers to successively close the five pairs of contacts 34 and 35 during the successive select-

ing signal intervals so that the set of selecting magnet 79 is successively connected to the contact 81 of the line relay and is operated in accordance with the selecting signal intervals. As the relay armature is shifted during the selecting signal intervals the circuit of the start magnet 77 is opened and closed but at such times the high portion of the stop cam 73 passes in front of the nose on the upper end of the stop arm 76, so that the 70 vibrations of the stop arm are very slight. But during the spacing interval at the end of each signal, the relay armature will engage its contact 81 and the nose of the stop arm 76 will pass into the recess of the cam 73 and engage the shoulder 75 to arrest the receiver cam. The receiver cams are driven at a greater angular speed than the transmitter cams. For this purpose the connecting gears 49, 51 and 52 between the drive 75 shafts for the transmitting and receiving cams are so proportioned that the shaft 53 is driven slightly faster than the shaft 39, for example in the ratio of 13 to 12, and the governors of the motors of the instruments at different stations are set to run 80 at the same or substantially the same speed. Then to insure that the receiver cam will pass through its five selecting operative positions during the mid-portions of the selecting intervals of the signals, the receiver cam recesses 1, 2, 3, 4 and 5, are angularly spacer farther apart than the corresponding recesses of the transmitter cam 85 in correspondence with the speed ratio of 90 their drive shafts, and these receiver cam recesses and the lugs 37 on the associated switch controllers are so proportioned that the different operating positions of the receiver cam are angularly considerably 95 shorter than the corresponding operation 100 positions of the transmitter cam, and the operating positions of the receiver cam do not, like those of the transmitter cam, overlap. With this arrangement, by properly 105 adjusting the receiver cam, the line relay will shift its armature while all of the pairs of receiver contacts 34 and 35 are held open, and the selective operation of the receiving printer will be properly affected, 110 even though the motor speeds and other conditions at different connected stations may vary. By means of the screw 74 the receiver cam is adjusted relatively to its stop cam 73 to compensate for variations 115 in its own starting operation and so that it will pass through its first selecting operating position during the first selecting 120 interval of each signal.

With the arrangement shown, the transmitter and receiver distributors, their operating motor and the transmitter controlling key board are conveniently arranged upon a common base, the rear extension 12 of which is provided with con- 125 130

tact clips by which the parts of the unit can be suitably connected to the line battery and receiving printer.

Obviously, changes may be made in the 5 details set forth without departure from the essentials of the invention as defined in the claims.

I claim as my invention:

1. In a telegraph apparatus, sets of transmitting and receiving contacts, corresponding sets of controllers therefor, separate rotary cams, each operable in order upon the controllers of one of said sets, selecting devices for modifying the operation of said 10 transmitter controllers, stops for arresting said cams in normal position, means for mechanically setting said selecting devices and releasing said transmitter stop, means responsive to the signals for releasing said receiver stop and variably connecting said receiver contacts to a source of current supply, and rotary motor driven means for continuously advancing said cams at each operation thereof.
2. In a telegraph apparatus, sets of transmitting and receiving contacts, corresponding sets of controllers therefor, separate rotary cams, each operable in order upon the controllers of one of said sets, selecting devices for modifying the operation of said 15 transmitter controllers, stops for arresting said cams in normal position, means for mechanically setting said selecting devices and releasing said transmitter stop, means responsive to the signals for releasing said receiver stop and variably connecting said receiver contacts to a source of current supply, a common motor and rotary means operated thereby for continuously advancing the 20 respective cams at each operation thereof.
3. In a telegraph apparatus, sets of transmitting and receiving contacts, corresponding sets of controllers therefor, separate rotary cams, each operable in order upon the controllers of one of said sets, selecting devices for modifying the operation of said 25 transmitter controllers, stops for arresting said cams in normal position, means for mechanically setting said selecting devices and releasing said transmitter stop, means responsive to the signals for releasing said receiver stop and variably connecting said receiver contacts to a source of current supply, a common motor and rotary means operated thereby for continuously advancing the 30 respective cams at each operation thereof.
4. In a telegraph apparatus, sets of transmitting and receiving contacts, corresponding sets of controllers therefor, separate rotary cams, each operable in order upon the controllers of one of said sets, selecting devices for modifying the operation of said 35 transmitter controllers, stops for arresting said cams in normal position, means for mechanically setting said selecting devices and releasing said transmitter stop, means responsive to the signals for releasing said receiver stop and variably connecting said receiver contacts to a source of current supply, a common motor and rotary means operated thereby for continuously advancing the 40 respective cams at each operation thereof.
5. In a selecting telegraph apparatus, a number of pairs of spring contacts, a corresponding set of controllers therefor, a rotary cam member cooperating with said controllers and normally holding said pairs of contacts open, and having portions for permitting the shift of said controllers and the closing of said pairs of contacts in order and at spaced intervals, a stop for arresting said cam in normal position at the end of each signal period, a relay means controlled thereby for releasing said stop and variably connecting said contacts to a source of current supply, and rotary power-actuated means for continuously advancing said cam during each complete operation thereof.
6. In a selecting telegraph apparatus, a number of pairs of spring contacts, a corresponding set of controllers therefor, a rotary cam member cooperating with said controllers and normally holding said pairs of contacts open, and having portions for permitting the shift of said controllers and the closing of said pairs of contacts in order and at spaced intervals, a stop for arresting said cam in normal position at the end of each signal period, a start magnet for releasing said stop, rotary power-actuated means for continuously advancing said cam during each complete operation thereof, and a relay responsive to each received signal for operating said start magnet and variably connecting said contacts to a source of current supply.
7. In a selecting telegraph apparatus, a number of pairs of spring contacts, a corresponding set of controllers therefor, a rotary cam member cooperating with said controllers and normally holding said pairs of contacts open, and having portions for permitting the shift of said controllers and the closing of said pairs of contacts in order and at spaced intervals, a stop for

- arresting said cam in normal position at the end of each signal period, a start magnet for releasing said stop, power-actuated means for continuously advancing said cam 5 during each complete operation thereof, and a relay responsive to each received signal, one of each pair of contacts being connected in circuit with the normally engaged contact of said relay, and said start magnet being permanently connected in circuit with the normally disengaged contact thereof. 10
8. In a telegraph apparatus, a set of electrically responsive selecting devices, a relay responsive to received signals, contact mechanism including a rotary member for connecting said selecting devices in order during each signal period to the normally engaged contact of the line relay, power-actuated means for continuously advancing said rotary member during each signal period, a stop for arresting the same at the end of each signal, and a start magnet for releasing said stop permanently 25 connected in circuit with the off-normal contact of the relay. 20
9. In an apparatus for telegraph systems employing signals each consisting of a starting interval, a definite number of selecting intervals and a spacing interval, the combination of sets of transmitting and receiving contacts arranged in pairs, rotary cylindrical cams, each operable upon one of said sets of contacts in order, the transmitter cam having successively operating peripheral portions corresponding to the signal intervals and the receiver cam having operating peripheral portions corresponding to the mid-portions only of the 30 selecting intervals of the signals, and means under control of start-stop clutches for continuously advancing said cams during each complete operation thereof. 35
10. In an apparatus for telegraph systems employing signals each consisting of a starting interval, a definite number of selecting intervals and a spacing interval, the combination of sets of transmitting and receiving contacts arranged in pairs, rotary cylindrical cams, each operable upon one of said sets of contacts in order, the transmitter cam having successively operating peripheral portions corresponding to the signal intervals and the receiver cam having operating peripheral portions corresponding to the mid-portions only of the selecting intervals of the signals and having an angular spacing relatively greater 40 than the corresponding portions of said transmitter cam, and means under control of start-stop, slip-friction clutches for continuously advancing said cams at each complete operation thereof and at correspondingly different angular speeds. 45
11. In an apparatus for start-stop telegraph systems employing a definite interval code, sets of transmitter and receiver contacts, rotary start-stop cylindrical cams, each operable in order upon one of said sets of contacts, a set of permutation bars, means controlled thereby for mechanically modifying the operation of the transmitter cam during the selecting intervals of the signals, finger keys, each arranged to shift each of said bars and set them in different combinations, means operated by each key for starting the transmitter cam and means responsive to the signals for starting the receiver cam and variably controlling the circuits of the receiver contacts. 50
12. In an apparatus for start-stop telegraph systems employing a definite interval code, sets of transmitter and receiver contacts arranged in pairs, corresponding sets of controllers, rotary, start-stop, cylindrical cams; each operable in order upon one of said sets of controllers, a set of permutation bars, selectors operated thereby for mechanically modifying the operation of said transmitter cam during the selecting intervals, finger keys each arranged to start said transmitter cam and shift each bar to one of two positions, and means responsive to the signals for starting said receiver cam and for modifying the circuits of the receiver contacts. 55
13. In an apparatus for telegraph systems employing signals separated by spacing intervals and each comprising a starting interval and a definite number of selecting intervals, the combination of sets of transmitting and receiving contacts, rotary start-stop cams, each operable upon one of said sets of contacts in order, stops for arresting said cams in normal position, said transmitter cam having overlapping peripheral portions corresponding to the signal intervals and brought into operation successively by its movement from normal position, to transmit the signals, the receiver having spaced peripheral portions brought into operation by its movement from normal position successively and during the mid-portions only of the selecting intervals of the signals, and motor driven means for continuously advancing each of said cams at each operation thereof. 60
14. In an apparatus for telegraph systems employing signals separated by spacing intervals and each comprising a starting interval and a definite number of selecting intervals, the combination of sets of transmitting and receiving contacts, rotary start-stop cams, each operable upon one of said sets of contacts in order, stops for arresting said cams in normal position, said transmitter cam having overlapping peripheral portions corresponding to the signal intervals and brought into operation successively by its movement from normal position, to 65

transmit the signals, the receiver having spaced peripheral portions brought into operation by its movement from normal position successively and during the mid-portions only of the selecting intervals of the signals, the peripheral portion of said transmitter cam corresponding to the spacing intervals extending through a greater angular space than any other of said portions, means for controlling said transmitter cam and contacts independently of the signals and arranged to permit the continuous rotation thereof through successive signal periods, means responsive to the signals for controlling the receiver cam and contacts, and power means for continuously advancing each of said cams at each operation thereof.

HOWARD L. KRUM.
